UNITED STATES PATENT OFFICE.

ALLEN B. NORTON, OF CLEVELAND, OHIO.

METAL MOLD.

Application filed May 25, 1923. Serial No. 641,359.

To all whom it may concern:

Be it known that I, ALLEN B. NORTON, a citizen of the United States, residing at Cleveland, in the county of Cuyahoga, State 5 of Ohio, have invented certain new and useful Improvements in Metal Molds, of which the following is a specification.

This invention relates to metal molds for casting light weight metals having a high 10 crystallization shrinkage, as compared with iron. In particular, it is concerned with a mold for casting thin walled articles composed of aluminum or its alloys.

Heretofore it has been found difficult to 15 cast successfully articles composed of aluminum or aluminum alloys of the dimensions most desirable in articles such as cooking utensils. Such articles are of various sizes and shapes but nearly all have relatively 20 thin walls or wall portions which are not easily cast of the metals described in permanent molds of the present types with which I am familiar.

Another difficulty experienced in casting 25 such articles is that when the articles are cast on their sides or edges, their vertical dimensions are so great that the molten metal must travel a considerable vertical distance from the top of the mold to the 30 bottom of the casting cavity, which distance, in many instances, is sufficient to cause agitation or breaking up of the molten metal as it enters the casting cavity and the formation of pores, pits and other imperfections 35 in the surface of the casting which renders attainment of a polished surface free from blemishes difficult or impossible.

I have found however that articles of the 40 class described having smooth substantially unpitted surfaces may be cast successfully of aluminum or aluminum alloys in permanent molds and with walls or wall portions much thinner than has previously been possible by 45 suitably shaping and positioning a gate with respect to the casting cavity, so that the entering molten metal need flow only a minimum distance through the shallow portions 50 of the casting cavity in which the thin wall portions of the article are cast. Furthermore I have found that by use of a new and 55 improved form of gate, I can cast articles of the class described having relatively large vertical dimensions substantially without any of the present disadvantages which 60 have been partially enumerated above.

One object of my invention is to provide

a new and improved gate for conducting molten, light weight metal, under the action of gravity, into a casting cavity from a considerable height in a manner to prevent 60 leaping or splashing of the metal or other agitation thereof sufficient to result in entrapping air in the metal and to cause porosity or surface pitting of the casting; to avoid heating certain parts of the mold ex- 65 cessively; and to separate light weight, floating impurities from the molten metal before the metal enters the casting cavity.

Another object is to provide a new and improved gate for conducting molten, light 70 alloy metal into a vertically elongated casting cavity from a point well above the upper extremity of the cavity substantially without harmful agitation.

Another object is to construct a multiple 75 part mold having pivotally mounted bodies and a stationary or slideable mold body carrying a movable core and co-operating therewith.

Another object is to construct a multipart 80 mold comprising a three part mold body with two parts arranged side by side and the third part arranged to co-operate with one end of these parts.

Another object is to construct a metal 85 mold for casting flat or shallow pan-like articles in which trimming of casting is reduced to a minimum or entirely obviated except at the points of attachment thereto of gates and risers. 90

Another object is to provide a new and improved arrangement of gate and feeder cavities with respect to a casting cavity for articles having thin wall sections whereby 95 the entering molten metal is caused to flow a minimum distance through the shallow portions of the casting cavity.

Other objects will appear and be pointed out hereinafter.

In the drawings attached hereto and 100 forming a part of this specification;

Fig. 1 is a top plan view of one form of mold constructed in accordance with my invention.

Fig. 2 is a similar view but showing the 105 pivoted mold bodies in a partly separated position and the core withdrawn preparatory to removal of a casting.

Fig. 3 is an elevation partly in cross section taken on line 3—3 of Fig. 1 showing a 110 casting in the casting cavity.

Figs. 4, 5, 6, 7 and 8 are fragmentary,

horizontal cross sections taken on lines 4—4, 5—5, 6—6, 7—7, and 8—8 of Fig. 3 showing relative sizes of various parts of the gate and feeder cavities.

5 Fig. 9 is an end elevation partly in section taken on line 9—9 of Fig. 1 with the main core and one mold part removed showing the relative sizes of casting, gate and feeder cavities indicated.

10 Figs. 10 and 11 are respectively outer end elevation and vertical cross sections of the main core.

Fig. 12 shows in perspective a casting as made in the improved mold.

15 Fig. 13 is a perspective view of an insert for the main core, and

Fig. 14 is a diagrammatic view of a modified form of gate, feeder and coating cavities.

20 In the drawings in which I have illustrated one form of mold embodying my invention and adapted for casting a thin walled, shallow article such as a frying pan, 1 indicates a mold base comprising a flat top

25 2 and suitable supporting legs or flanges 3. At the rear of base 1 a pivot pin 4 is secured to the base in an upright position. Two similarly formed complementary mold bodies 5 are pivoted to pin 4 by outstanding 30 lugs 6, the mold bodies 5 being slidably seating on the base and being adapted to swing about pin 4. 7 indicates another mold member removably secured to base 1 on the top surface thereof and in a position to engage and co-operate with one end of each of

35 mold bodies 5 in certain positions of the latter. Suitable securing means for mold body 7 are indicated at 8, where bolts are shown passing through a flange portion 9 of

40 body 7 but if desired bolt 8 may be omitted and the mold body left free to be moved on base 1. Suitable pilot or positioning means for determining the proper positions of the several mold bodies may take various forms 45 but I have shown dowel pins 1^a mounted in the top of base 1 and engaging in recesses in the meeting faces of the mold bodies which have been found satisfactory.

In the meeting faces of mold bodies 5, 50 recesses are suitably formed to constitute gate, feeder, casting and riser cavities when the bodies are in engagement with each other. These cavities are designated respectively by numerals 10, 11, 12 and 13 on Fig.

55 3. Preferably the inner face of mold body 7, or the surface thereof which is adjacent one end of mold bodies 5, is substantially vertical, although if it is desired to form a casting in a position other than substantially

60 vertical as is here shown, this surface may be correspondingly inclined. The inner face 14 of mold body 7 forms the edge or end walls of the casting cavity 12, the remaining outer sides of the casting cavity being 65 formed by the walls of the mold bodies 5.

Mold body 7 carries a movable core 15 slidably mounted therein in a substantial horizontal position. This core is substantially circular in cross section, and is of sufficient length so that its inner end projects beyond the inner surface 14 of mold body 7 and into casting cavity 12 where the inner end and exposed side-walls of the core constitute walls for forming the interior of the casting cavity.

70 Core 15 is preferably hollow with its walls suitably proportioned in thickness to the size and nature of the casting desired. To facilitate movement of core 15 in mold body 7, as is desired for ready removal of the casting from the casting cavity, bracket 16 is secured to the mold body 7 by suitable means indicated generally at 17. This bracket is perforated, as at 18, to receive a screw threaded rod 19 engaging in a threaded hole 20 in cross bar 21 secured to core 15. Collars 19^a pinned to rod 19 on either side of bracket 16 prevent longitudinal movement of the rod through the bracket and when the rod is revolved, as by hand wheel 19^b, the rod served 75 to move core 15 relative to mold body 7. It will be obvious that other means may be used for actuating core 15 in mold body 7, but such means are considered mechanical equivalents of the form herein illustrated and accordingly are not shown or described.

80 It will, of course, be obvious that the core 15 may be dispensed with in molds for certain types of castings, for example, flat or relatively shallow articles, or flanged articles having a flange extending away at an obtuse angle, in which case the mold body 7 may present a continuous surface 14 to mold bodies 5 instead of being cut away for a core 85 as here shown.

105 22 designates a core pin adapted to seat on the top of the mold bodies 5 and 7 and to pass through an opening in the meeting faces thereof and projected into the casting cavity for the purpose of forming a cored out opening in a handle lug 28 on the casting.

110 It will be understood that other forms of core pins may be used when occasion demands, and that the nature of the casting being made will to some extent determine the location of the pin with respect to the mold bodies. All such pins are however, considered to be the equivalent of the one herein shown.

115 Main core 15 has a substantially circular side surface adjacent the inner end thereof to form a substantially circular inner wall for the casting. It will be observed however, that upon opposite sides of the casting this flange has an outwardly projecting irregular portion or lip. To facilitate machining of the core and thereby cheapen its cost of manufacture, inserts 15^a having corresponding projections 15^b have been pro- 120 125

vided to seat and be secured in recesses 15^b in the sides of the core adjacent the points where these irregular portions or lips are to be formed in the casting. In this manner the core may be turned to size in a lathe, while the inserts with the irregular surfaces may be machined separately and then fitted into the core. In casting articles of the class shown, such core structure is highly desirable, and so far as I am aware, is new and accordingly is being claimed broadly.

The new and improved form and arrangement of the casting and riser cavities contribute to the casting of articles requiring sound, non-porous smooth surfaced articles of the class described, with a minimum of grinding and other finishing operations being required. By reason of the gate and feeder cavity communicating with the casting cavity along the rear side thereof which corresponds to the bottom of the casting, it will be evident that the only finishing operation required will be a severing of the gate metal and the bottom of the casting and riser metal from the handle lug. The cost of the castings is thus greatly reduced.

For articles of the class shown where the article is cast in an upright position and the molten metal is led under the action of gravity through a considerable vertical distance, the improved form of gate and feeder cavities illustrated are preferable.

The gate indicated as an entirety at 10 comprises a downwardly extending inlet passage 10^a inclined slightly to the vertical which communicates at its lower end with a restricted passage 10^b which turns abruptly about point 20 and extends upward and rearward or away from the casting cavity to a point 21 above point 20, the passage thus serving as a means of retarding and more or less controlling the speed of flow of the entering molten metal as well as forming a liquid seal which tends to trap out light impurities and prevent their entry into the casting cavity. From point 21 passage 10^b curves downwardly and forwardly, or toward the casting cavity, at a progressively increasing angle to the vertical and flaring out adjacent to the feeder cavity in a vertically elongated, relatively narrow fan shaped discharge passage 10^c which preferably has a small width as compared with other parts of the gate 10 and an upright dimension approximately equal to the height of the feeder cavity 11.

The feeder cavity preferably extends upwardly to a point above the main portion of the casting cavity 12. Where projections from the main casting are to be cast above the main casting cavity, as handle stud 28 (Fig. 12), a riser cavity 13 may be provided to insure proper filling of the stud cavity.

Feeder cavity 11 is joined to casting cavity 12 by a short narrow passage 11^a which

may be formed conveniently by projecting ribs or ridges on the faces of the mold halves, as shown in Figs. 2 and 3.

Fig. 12 shows, in perspective, an article with gate and riser attached as it appears when cast in a mold of the foregoing description. 24 indicates the casting proper which is a thin walled, shallow or pan-like article having a flat bottom 25, sides 26 provided at diametrically opposite points with outturned lips 27, and a short handle 28. 29 indicates a quantity of metal forming a riser in communication with handle 28. 30 indicates a quantity of metal formed in feeder cavity 11 and connected to article 24 by a thin neck 31. A portion of the gate metal formed in gate 10 is indicated at 32.

In the operation of the mold illustrated, the mold bodies 5 are swung into assembled relation with mold bodies 7, and main core 15 and core pin 22 are brought to their proper positions with respect to the mold bodies and casting cavity after the parts forming the cavities have been coated with a suitable mold coating composition. The mold bodies, and chiefly those in which the gate and feeder cavities are formed, having first been brought to the desired operating temperature, as by applying a heating flame thereto or by other suitable means, a molten metal which may consist of aluminum or its alloys or other light weight metals having relatively high crystallization shrinkage as compared with iron is poured into the inlet passage 10. It immediately fills the pocket or passage 10^b at the bottom of passage 10^a, thus effectually sealing the control passage 10^b and preventing light impurities on the surface of the molten metal from entering passage 10^c. The metal with its velocity materially decreased flows upwardly through passage 10^b and passes downwardly and forwardly into the discharge passage 10^c at a velocity materially less than if it had fallen from the top of the mold bodies without interruption, and thence flows into feeder and casting cavity smoothly and without leaping or sufficient velocity to cause harmful agitation, breaking up or splashing of the metal which may result in the entrapping of air therein and the consequent production of porous or pitted castings. As the pouring proceeds, the molten metal enters the bottom of the casting cavity and rises in the casting and feeder cavities with the entering metal tending to flow outwardly across the top of the molten metal therein, which action is to some extent continued, due to the curving upper surface of passage 10^c, until the feeder cavity 11 is completely filled. By providing an enlarged feeder cavity, a quantity of molten metal may be maintained in communication with the metal in the casting cavity until it has solidified to compensate for voids in the casting by

shrinkage of the casting during solidification, the resulting casting being thus rendered substantially free from crystallization shrinkage defects.

- 5 The first entering metal will presumably impinge against the part of the core directly opposite the opening 11^a but due in part to the configuration of the gate subsequently entering metal will flow onto the top of the 10 molten metal already in the casting cavity, and successively strike against higher parts of the core thus avoiding the excessive heating of certain portions of the mold or core. However, I have provided a boss 23 on the 15 core adjacent the point of first contact of the molten metal therewith for the double purpose of rapidly dissipating heat from the face of the core in contact with the first entering molten metal and for providing a 20 pad to which an insert could be attached should the outer face of the core become worn or corroded. In practice this boss has not been found necessary however.

Although the particular type of gate and 25 feeder herein shown is particularly applicable to the type of casting illustrated, (it may be utilized to advantage with other types of castings not illustrated,) it may be utilized to advantage with other types of 30 castings wherein the vertical height of the casting cavity is relatively large.

Furthermore, it will be obvious to those skilled in the art that this improved form 35 of gate and riser can be equally as well employed where the gate, feeder and casting cavities are in substantial alignment instead of being transversely positioned as shown herein. With such arrangement of cavities, it is often possible to use only two movable 40 mold bodies instead of three as here shown, and as an illustration of such molds reference is made to Patent 1,296,588 granted March 4, 1919, to J. H. Bamberg.

The arrangement of the gate and feeder 45 cavities at substantially right angles to the medial part of the casting cavity is of especial importance where the casting has a thin section, since it is in accord with the principle of causing the molten metal to flow a 50 minimum distance thru narrow or shallow casting cavities. With the illustrated arrangement of cavities the molten metal flows each way laterally from the feeder cavity thus traveling the minimum distance thru 55 the narrow cavity to reach all parts of the casting cavity. Somewhat similar results could be obtained by feeding metal into opposite edges of the casting cavity thus causing the metal to flow from opposite sides 60 toward the medial portion of the casting cavity.

If desired the oppositely located feeder 65 cavities may be supplied by a single gate outside the casting cavity as is indicated diagrammatically in Fig. 14 where 33 in-

dicates a casting cavity, 34 the opposite feeder cavities, 35 the gate and 36 a passage connecting the two feeder cavities.

I do not wish to be understood as limiting my invention to the particular article shown but on the contrary contemplate the casting of many different sizes and types of articles, for culinary and other uses and including pans of various depths, griddles, covers, plates and similar articles.

Having thus described the invention in some sufficient detail to permit those skilled in the art to practice the same, what is desired to be secured by Letters Patent is defined by what is claimed.

What is claimed is:

1. A mold for articles of the class described comprising in combination a mold base, a mold body on the top thereof, a main core in the said mold body, and other mold bodies cooperating with each other and the first said mold body and core to form gate, feeder, and casting cavities.

2. A mold for articles of the class described comprising in combination, a mold base, a mold body seated on the top thereof, a main core movably mounted in the said mold body, and other mold bodies seated on the mold base and cooperating with each other, the first said mold body and the core to form gate, feeder and casting cavities.

3. A mold for articles of the class described comprising in combination a mold base, a mold body seated on the top thereof, a main core in the said mold body, and other mold bodies pivoted to and slidable on the said base and cooperating with each other and the first said mold body to form gate, feeder and casting cavities.

4. A mold for articles of the class described comprising in combination, a mold base, a mold body seated in the top thereof a main core movably mounted in the said mold body, a vertical pivot pin attached to the said base and mold bodies pivoted on the said pin and seated for sliding movement on the said base.

5. A mold for articles of the class described comprising in combination, a mold base, a mold body seated in the top thereof, a main core horizontally slidable in the said mold bodies, and other mold bodies slidably mounted on the said base and cooperating with each other and the first said mold body and core to form gate, feeder and casting cavities.

6. A mold for articles of the class described comprising in combination a mold base, a mold body secured to the said base a main core slidably mounted in the said mold body, an upright pivot pin secured to the said base, mold bodies pivoted to the said pin and slidable on the said base, and means for moving the main core in the first said mold body.

7. A mold for articles of the class described comprising in combination a mold base, a mold body secured to the said base a main core horizontally and slidably mounted in the said mold body, an upright pivot pin secured to the said base and other mold bodies pivoted to the said pin and slidable on the said base, and means for moving the main core in the first said mold body. 5
- 10 8. In a mold for casting shallow pan like articles, the combination with a mold base, of a mold body mounted thereon having a substantially vertical inner face, a main core in the said mold body projecting inwardly beyond the said inner face and adapted to form the inner surface of a shallow, pan-like casting cavity, and other mold bodies mounted on the said mold base to engage with the inner face of the first 15 said mold body, the meeting faces of the last said mold bodies being cut away to form the outer surfaces of the gate, feeder and casting cavities. 20
9. In a mold for casting shallow pan like articles, the combination with a mold base of a mold body mounted thereon having a substantial vertical inner face, a main core slidable horizontally in the said mold body and adapted to project inwardly beyond the said inner face to form the inner surface of a shallow, pan-like casting cavity, and other mold bodies swingably and slidably mounted on the said mold base and adapted to engage with the inner face of the first said mold body, the meeting faces of the last said mold bodies being cut away to form the outer surfaces of the gate, feeder and casting cavities. 25
10. In a mold for casting pan-like articles, 40 the combination of a mold base, a plurality
- of mold bodies slidably mounted thereon, and having gate, feeder and casting cavities formed in the meeting faces of the said mold bodies, one mold body having a substantially plane surface to form an end wall 45 for the casting cavity, and a core mounted in the last said mold body and projecting inwardly beyond the said plane surface, the inner end and sides of the said core constituting certain of the inner walls of the 50 said casting cavity.
11. In a mold for casting culinary utensils, the combination of a mold base, a plurality of mold bodies slidably mounted thereon having gate, feeder and casting cavities 55 formed therebetween, one mold body having a substantially plane surface to form end walls for the casting cavity, and a core horizontally and slidably mounted in the said mold body and projecting inwardly beyond the said plane surface, the inner end and sides of the said core constituting certain 60 of the inner walls of the said casting cavity, and means for actuating the said core.
12. A mold for articles of the class described comprising in combination a mold base, an upright pivot pin secured thereto, mold bodies pivoted to the said pin and slidable on the said base, a mold body secured to the said base and cooperating with 65 the said pivoted mold bodies, and a main core circular in cross section adjacent its inner end and horizontally and slidably movable in the said mold body, the said core having inserts in a side thereof adjacent the 70 inner end.

In testimony whereof, I hereunto affix my signature.

ALLEN B. NORTON.
